UNITED STATES PATENT OFFICE

ROSCOE C. HOFFMAN, OF DETROIT, MICHIGAN

DESIGN FOR AN AUTOMOBILE

Application filed January 28, 1932. Serial No. 42,648. Term of patent 7 years.

To all whom it may concern:

Be it known that I, ROSCOE C. HOFFMAN, a citizen of the United States, residing at Detroit, in the county of Wayne and State of Michigan, have invented a new, original, and ornamental Design for Automobile, of which the following is a specification, reference being had to the accompanying drawings, forming a part thereof, and in which—

Fig. 1 is a side elevation of an automobile incorporating my new design;

Fig. 2 is a plan view of the automobile shown in Fig. 1;

Fig. 3 is a front elevation of the automobile shown in the foregoing figures;

Fig. 4 is a rear elevation of the automobile shown in the foregoing figures.

I claim:

The ornamental design for an automobile, as shown.

ROSCOE C. HOFFMAN.
